CLAIM

The ornamental design for a combined liquid measuring vessel and bottle, as shown and described.

DESCRIPTION

FIG. 1 is a top, front and left side perspective view of a combined liquid measuring vessel and bottle showing our new design;

FIG. 2 is a left side elevation thereof, the right side elevation is a mirror image thereto except for the threading on the liquid measuring vessel;

FIG. 3 is a top plan view thereof;

FIG. 4 is a front elevational view thereof;

FIG. 5 is a rear elevational view thereof;

FIG. 6 is a bottom plan view thereof;

FIG. 7 is a perspective view shown in the exploded condition;

FIG. 8 is a side elevation of the liquid measuring vessel shown separately, the opposite side is a mirror image thereto except for the threading; and,

FIG. 9 is a top plan view of FIG. 8.

The measuring vessel is shown without the bottle in FIGS. 8 and 9 for illustrative purposes.
